FREQUENCY STABILIZATION

Marc Ziegler and Manuel Julio Kobilsky, Buenos Aires, Argentina, assignors to Hartford National Bank and Trust Company, Hartford, Conn., as trustee

Application November 3, 1942, Serial No. 464,380

9 Claims. (Cl. 179—171.5)

1

The present invention relates to frequency stabilization and more particularly to the stabilization at a desired value of the frequency of an oscillator.

In connection with the problem of stabilizing the frequency of an oscillator at a desired value, which is of great importance in radio technique, several solutions have heretofore been proposed. For instance, the use of very selective circuits with great physical constancy, such as crystals, spatial circuits and tuning forks, permits of the construction of oscillators the frequency of which does not vary more than a small fraction of its nominal predetermined value.

The frequency of such an oscillator is, however, so well defined by the physical constants of the circuits used that it cannot be shifted, even if desired, from its original value. Only a phase shift can be forced on the oscillation obtained, either by using the properties of electrical circuits or by introducing a time-retarding device. By phase modulation a corresponding frequency modulation may be created at the output, but the frequency of the oscillator itself does not vary, and the mean frequency of the output signal remains equal to it.

In many cases, however, it is not desired to obtain merely a frequency of rigorously known value, but to have an oscillator which shall automatically adjust itself exactly at a frequency which is known only approximately and which may be varying in time. Again, it may be desired to modulate directly the frequency of an oscillator by periodic variation of one of the circuit constants.

All these cases necessarily require the use of suitable oscillator arrangements the constants of which may readily be modified, so that the frequency may be changed as a function of a controlling magnitude. The control of the circuit may be either mechanical, as by means of variable condensers, moving cores and the like, or electrical, as by means of magnetic saturation, variation of dielectric constant with temperature, reactance tubes and the like, and of these methods, the purely electrical one involving reactance tubes is the most generally used nowadays.

The controlling magnitude may be obtained in one of two general ways, namely, either by operating on the basis of the phase difference between the oscillation to be controlled and a pilot oscillation, or by obtaining it from a frequency responsive device which measures the frequency difference between said oscillations.

The first way leads to a synchronization of the

2

two oscillations and to a resultant frequency which is rigorously equal to that of the pilot. The classical phase measuring methods are limited however to phase differences smaller than $\pi/2$ which is a given limitation. The second method gives rise merely to a reduction of the frequency, though this reduction can generally be as large as desired.

10 The present invention is more particularly concerned with the frequency reduction methods of stabilization.

The known systems of frequency control by frequency reduction utilize, for obtaining the controlling magnitude, the frequency responsive properties of selective circuits. Hence the absolute stability obtainable cannot be better than the absolute stability of the said discriminator circuits, and this suggests the use, for the discriminator, of high quality circuits such as those hereinbefore mentioned. While the use of such circuits is, of course, possible, it will not answer the requirements of linear response to frequency variations over a relatively wide range, which must be satisfied in, for instance, frequency modulation problems. If a wide frequency swing has to be discriminated linearly, only less selective circuits can be used, whereby the inherent instability thereof is introduced into the system.

Furthermore, the response of the common discriminator circuits, and, therefore, the resulting controlled frequency, depend either on the amplitude of the applied signal and on the value of a compensating voltage, or on the correct balance of a symmetric detector arrangement, all 30 of which factors are possible causes of drift from the exact adjustment.

The method of the present invention and the devices for the realization thereof while having the same basic idea as other frequency stabilizing arrangements, namely, to measure the frequency difference between the oscillation to be stabilized or controlled and a pilot oscillation and to use the magnitude so obtained for automatically reducing the frequency difference as much 40 as possible, utilizes, in contradistinction to the prior art, a compensated frequency meter the output of which is zero for a predetermined frequency independently of the battery tension applied.

45 By frequency meter is meant herein a frequency responsive device commonly known as such, which includes only resistances and capacities. Accordingly the present invention dispenses with the use of a symmetric discriminator design comprising selective inductance and capacity cir-

cuits and with the use of a stabilized compensating tension.

Since frequency meters have already been discussed in detail elsewhere (see Frequenziometri elettronici a desviazione, Alta Frequenza, F. Vecchiacchi, May 1937) it is deemed sufficient for the understanding of the present invention, to recall that the output current is provided by a number of condenser discharges which is equal, during any time, to the number of positive phases of the signal applied to the apparatus.

If the RC time of the condenser circuit is sufficiently small compared with the period of the highest frequency to be measured, the condenser is each time charged to the same potential and discharged completely, so that the discharges are equal and the mean value of the current, taken over some time including a sufficiently large number of periods, is proportional to the number of periods and hence to the frequency. Moreover, if the amplitude of the signal applied does not influence the loading voltage, the output is independent of this amplitude. It can also be shown that, if the frequency of the signal varies, the output reproduces the variation correctly so long as the variation is slow as compared with the longest period of the frequencies passed during the excursion, and that, even if the frequency modulation has a period of the same order as or even smaller than said longest period, the average value of the output current, taken over a long time, will still be proportional to the central frequency.

These general properties of the frequency meter will be utilized in accordance with the present invention for obtaining an improved method and means for frequency stabilization and for obtaining other derivative advantages arising out of the application of the said improved method and means in particular problems, as will hereinafter be more particularly explained.

In the drawing,

Fig. 1 is a block diagram illustrating the method of frequency stabilization of the present invention, and

Fig. 2 is a diagram illustrating a frequency modulated transmitter embodying frequency stabilization according to the present invention.

As already stated, the basic idea underlying the present method is to measure the frequency difference between the oscillation to be stabilized and the oscillation of a pilot, and it is therefore obvious that the frequency difference which is to be the direct cause of the controlling action to be applied to the oscillator, must be within the working range, an univocal function of the oscillator frequency.

Since, physically, the difference frequency can never have attributed to it a negative sign, it will be clear that the oscillator frequency will always have to be either higher or lower than the pilot frequency. Hence, the oscillator frequency must be stabilized at a frequency differing a predetermined amount from the pilot frequency, and this constitutes a particular feature of the present invention. The amount of difference is so chosen that the oscillator frequency will never pass the pilot frequency, taking into account all possible factors, including the possibility of frequency modulation.

The difference frequency, obtained as shown in Fig. 1, by applying the frequency of an oscillator 10 to a mixer 12 simultaneously with the output of a pilot 14, is applied to a frequency

70 4 meter 16 which produces an output proportional to said frequency difference.

Preferably the mixer 12 includes a convenient output filter from which the signal of frequency difference resulting from the mixing of the oscillator and pilot outputs is obtained.

It will be clear to those skilled in the art that, with the above arrangement any deviation from the desired frequency due to variation in the constants of the oscillator 10, as for example a change of capacity with temperature, cannot take place without causing an opposite effect proportional to the frequency change really taking place as the result of both effects. Analogously, with the well-known theory of negative feed-back, it can be shown that the frequency drift of the oscillator when connected to the correcting link is approximately A times smaller than the frequency drift without such link, A being a constant of the arrangement equal to the product of the sensitivity k of the frequency meter 16 in volts per kc. and the influence a of the reactance tube 22 in kc. per volt.

Since for successful operation of the novel method of frequency stabilization the output of the frequency meter must be properly compensated at all times, variations of the elements of this part of a practical arrangement would be considered as meriting attention, and indeed, investigation of this point has led to certain valuable features of the present invention, as will now be made clear.

It can be shown that the influence of relative variations da/a and dk/k of the constants a and k can be made practically negligible as it is equal to their product with the frequency difference divided by the factor $A=ak$, which can be made large in practice.

The influence of undesired variations in the compensating voltage V_b , when taken separately is, though by no means exaggerated, not at all negligible, but the present invention provides means for compensating this effect. As said before, the output current of the frequency meter is provided by a number of condenser discharges equal to the number of periods of the frequency applied. The output tension obtained is therefore proportional to the frequency, to the capacity of the condenser, to the voltage up to which the condenser has been charged and to the resistance through which the current is flowing.

If now the compensating voltage is obtained, by means of a potentiometer, from the same battery, which provides the tension for loading up the condenser, a change of battery tension will not affect the frequency for which the compensated output tension of the frequency meter is zero.

Such an arrangement is shown in the portion of Fig. 2 marked off with chain lines in which a battery B provides the operating tension for the frequency meter main tube 24, and the compensating tension λB is taken off a potentiometer 26 across said battery B . The frequency meter, as shown, likewise comprises a condenser C and an output resistance r , and is preferably provided with an output filter comprising resistances 28 and 30 and condensers 32 and 34.

In the operation of the frequency meter the oscillations present in the output of the mixer stage 12a are applied to the grid of the valve 24. During those half periods of the oscillation, for which the grid is positive with respect to the cathode of the valve, the latter will be conductive,

and practically the full voltage of battery B will be applied to capacitor C through load resistor r and diode 100. During the other half periods of the oscillation, when the grid of valve 24 is negative with respect to the cathode, capacitor C will be discharged through diode 101, resistor g and the external circuit including battery B, anode resistor 104 and potentiometer 26.

Resistors 102 and 103, included in the grid circuit of valve 24, are designed to transform the oscillation generated in the output circuit of the mixer stage 12a into a square wave. Across resistor r there is generated a discharge impulse of capacitor C every time the control grid of the valve 24 is positive with respect to the cathode of this valve, so that for each period of the oscillation applied to valve 24, an electrical impulse is obtained in such a form that the mean value of the tension developed across resistor r is proportional to the frequency of the oscillation applied to the control grid of valve 24. The tension so developed across the resistor r is compensated to zero for a given value of the frequency of the oscillation applied to the grid of valve 24 by means of the compensating tension λB so that the resulting voltage assumes positive and negative values in proportion to the sense and amount of deviation of the frequency of the oscillation from the given value.

The low pass filter following resistor r and constituted by resistors 28 and 30 and condensers 32 and 34 is adapted to suppress the alternating components in the mean voltage developed across the resistor r .

It can be deduced easily, that in such an arrangement, if $a'rCB > 1$, this product having the same significance as the factor $A=ak$ above mentioned, that the input frequency of the frequency meter for which the compensated output is zero, that is just the desired frequency difference between the pilot and the oscillator to be stabilized, is approximately equal to λ/rC .

It follows from this that said desired frequency can be adjusted to a predetermined value by varying either the potentiometer relation λ , the output resistance or the capacity of the frequency meter, which is a very interesting feature. These factors, moreover, can each be made adjustable with all the precision required and may present a high degree of constancy. For this reason, and because the frequency applied to the frequency meter (difference frequency) by which the relative variations of said factors are multiplied, may be of the order of only kc. or tenths of kc., a high degree of stability of the oscillator frequency when compared with the pilot frequency may be expected, even when working at frequencies as large as mc./s.

It may further be observed that variations of the proper frequency of the oscillator from the desired value are reduced to merely a certain fraction and reveal themselves as at tension at the output of the compensated frequency meter, so that the addition of a voltage indicator at said output makes it possible and easy to readjust, during operation, the proper frequency of the oscillator to the correct value, when it appears that over a long time, the frequency shift tends to increase to an inadmissible value.

The above-mentioned relationship between the desired frequency and the fractional compensating voltage, the output resistance and the capacity of the frequency meter, provides a very convenient solution of the big problem of having available a signal of readily and continuously ad-

justable frequency having all the stability of inherently non-variable oscillators, such as quartz oscillators and the like. The desired frequency can be changed, by choosing, for example another position of the potentiometer which determines the fractional compensating voltage. The potentiometer, which may be of the continuously or step-by-step variable type, may be calibrated in kilocycles for adjustment. Alternatively the output resistance or the capacity may be made adjustable, and in the latter event, the condenser of the frequency meter would be made variable or comprise a variable portion, as indicated by the arrow in broken lines in Fig. 2.

In the foregoing discussion the arrangement and method have been considered for the case of a non-modulated oscillator to be stabilized around a frequency differing a fixed amount from that of a non-modulated pilot. It is obvious that, since the response of the frequency meter does not, within a very large range, depend on the amplitude of the signal applied, either the oscillator to be stabilized or the pilot oscillator or both may be amplitude modulated, so long as the amplitude of the signal applied during the most pronounced amplitude minima, does not fall below the lower admissible limit.

If one or both of the oscillators is frequency modulated, stabilization is also possible, provided that care is taken that the predetermined frequency difference is sufficiently greater than the sum of the maximum excursions of the oscillators for the reasons hereinabove set forth.

If care is taken to make the response characteristic of the frequency meter linear between 0 and twice the desired frequency, and a suitable band pass filter, designed to cut out all frequencies above 30 c./s., is placed between the output of the frequency meter and the input of the reactance tube as indicated at 28 to 34 in Fig. 2, the theoretical results obtained can be applied without change to the central frequencies of the frequency modulated signals considered.

The frequency stabilization method of the present invention may also be applied to frequency modulated transmission, and an embodiment of such application is shown in Fig. 2. Here the transmitter antenna 36 is connected through a power output section 38, a driver or doubler 40 and a separator 42 to an oscillator 10a, which is connected to the mixer 12a of the frequency meter unit already described, and to a reactance tube 22a, which in the present instance acts both as stabilizer and as modulator.

The output of the frequency meter unit, after passing through the band pass filter 28 to 34, is conducted to the reactor tube through the secondary 44 of a transformer 46, the primary of which is connected to a source of intelligence, such as a microphone (not shown). Thus while the frequency meter arrangement maintains the central frequency constant, the output of the oscillator is also frequency modulated by superimposition of the intelligence factor derived from said secondary 44.

Those skilled in the art will appreciate from the foregoing description that the novel method and means for frequency stabilization of the present invention have a considerable number of advantages of great practical importance. We have seen that, for instance, the stabilizing arrangement described is very suitable for stabilizing the central frequency of a directly modulated oscillator, and a frequency modulated transmitter arrangement utilizing said arrange-

7
ment does not require more than a single quartz oscillator. Again, it is possible to make the stability of the central frequency depend practically only upon the stability of the quartz oscillator used. In general, the complete stabilizing arrangement does not require more than a single adjustment in order to adapt it to work at the desired frequency, and a change of the value of only one element makes it possible to stabilize the oscillator around different well-defined frequencies, a feature which may have many applications in radio communication. The number of tubes and parts is relatively small and there is nothing very critical in their assembly. Moreover, critical elements, such as a tube or a source of tension, may, as can be shown, have variations as large as 10% without affecting the validity of the results. Finally, it should be noted that the stabilizing arrangement does not use any tuned circuits. Hence it can be utilized at any frequency, and may be assembled and marketed as a universal frequency modulation and stabilization unit. Inclusion of the quartz pilot and of the oscillator gives a frequency modulation transmitting unit adapted to be directly connected to a frequency modulation transmitter.

10
15
Although the present invention has hereinabove been described with reference to certain preferred embodiments, we do not wish to be limited thereto as obvious modifications will occur to those skilled in the art without departing from the spirit and scope of the invention.

We claim:

1. The method of detecting frequency deviations of an electrical oscillation about a predetermined frequency value by means of a circuit arrangement comprising a direct current source and current interrupting means responsive to said electrical oscillation connected in series with said source, comprising the steps of generating electrical impulses for each period of said oscillation having an area substantially proportional to the voltage of said source and a duration smaller than the periods of the highest frequency to be detected, integrating said impulses to obtain an electrical quantity substantially proportional to the frequency of said oscillation and to said voltage, and simultaneously injecting another electrical quantity derived from said source in opposition to said first quantity to produce an output quantity which is compensated to zero independently of variations of said voltage at a frequency value of the oscillation equal to the said predetermined frequency value and the polarity and value of which are proportional to the deviation of said electrical oscillation from the predetermined frequency value.

2. The method of detecting frequency deviations of an electrical oscillation varying about a predetermined mean frequency by means of a circuit arrangement comprising a direct current source, a resistance and current interrupting means responsive to said electrical oscillation connected in series with said source and resistance, which comprises the steps of interrupting the current in said circuit in synchronism with half-waves of like sign of said oscillation to obtain voltage pulsations across said resistance, transforming said voltage pulsations into electrical impulses of like sign having an area substantially proportional to the voltage of said source, an amplitude independent of said oscillation and a duration smaller than the half-periods of the highest frequency to be detected, integrating said impulses to obtain an electrical

quantity substantially proportional to the frequency of said oscillation and to said voltage, and simultaneously injecting a fraction of said voltage in opposition to said quantity to produce an output quantity which is compensated to zero independently of variations in said source at a frequency value of the oscillation equal to the said predetermined mean frequency value and the polarity and value of which are proportional to the deviations of said electrical oscillation from the predetermined frequency value.

3. A compensated frequency discriminator for detecting frequency deviations of an electrical oscillation varying about a predetermined mean frequency, comprising a circuit containing a source of direct current and a resistance, means for interrupting the current in said circuit in synchronism with half-waves of like sign of said oscillation to obtain voltage pulsations across said resistance, means for transforming said voltage pulsations into electrical impulses of like sign having an area substantially proportional to the voltage of said source, an amplitude independent of said oscillation and a duration smaller than the half-periods of the highest frequency to be detected, means to integrate said impulses to obtain a potential substantially proportional to the frequency of said oscillation and to the voltage of said source, and means to connect a fraction of said voltage in opposition to said potential to produce an output potential which is compensated to zero independently of voltage variations in said direct current source at frequency values of the oscillation equal to the said predetermined mean frequency value and the polarity and value of which are proportional to the deviations of said electrical oscillation from the predetermined frequency value.

4. A compensated frequency discriminator for detecting frequency deviations of an electrical oscillation varying about a predetermined mean frequency, comprising a thermionic tube having a control electrode, an anode and a cathode, a resistance and a direct current source serially connected between the anode and cathode, means to apply said oscillation to said control electrode to produce voltage pulsations across said resistance in synchronism with half-waves of like sign of said oscillation, means to transform said voltage pulsations into electrical impulses of like sign having an area substantially proportional to the voltage of said source, an amplitude independent of said oscillation and a duration smaller than the half-periods of the highest frequency to be detected comprising a condenser having one electrode coupled to the anode circuit of said tube, two half wave rectifiers having anode and cathode electrodes, and a load resistance, the cathode of one of said rectifiers and the anode of the other rectifier being coupled to the other electrode of the condenser, one terminal of the load resistance being coupled to the other electrode of one of said rectifiers, and the other electrode of the second of said rectifiers and the other terminal of the load resistance being coupled to an intermediate voltage point in said direct current source, and means to integrate said impulses to produce a potential substantially proportional to the frequency of said oscillation comprising a filter coupled to said load resistance, the voltage at said intermediate point having a value substantially equal and opposite in sign to the value of said potential at a frequency value of the oscillation equal to the said predetermined mean frequency value.

5. A compensated frequency discriminator according to claim 4, in which the condenser is adjustable and varies the frequency at which the said compensated output potential is zero.

6. In a frequency stabilizing system, means for generating a main oscillation the frequency of which is to be maintained at a predetermined value, frequency adjusting means coupled to said generating means, means for generating a pilot oscillation differing from said main oscillation by a predetermined frequency, means for mixing said pilot and said main oscillations to produce a difference oscillation, a circuit including a direct current source and a resistance, means for interrupting the current in said circuit in synchronism with the half-waves of like sign of said difference oscillation to produce voltage pulsations across said resistance, means for transforming said voltage pulsations into electrical impulses of like sign having an area substantially proportional to the voltage of said source, an amplitude independent on said oscillation and a duration smaller than the half-periods of the highest frequency of said difference oscillation, means to integrate said impulses to obtain a potential substantially proportional to the frequency of said difference oscillation and to said voltage, means to connect said integrating means to said frequency adjusting means to maintain said main oscillation at said predetermined frequency value, and means to inject a fraction of the voltage of the direct current source in opposition to said potential to produce an output voltage compensated to zero independently of voltage variations in said direct current source at frequency values of the main oscillation equal to said predetermined value.

7. A frequency stabilizing system, according to claim 6, in which the relation between said voltage fraction and said potential is adjustable, and the frequency at which the main oscillation is stabilized is variable before and during operation.

8. In a frequency modulation system, means for generating an electrical oscillation the mean frequency of which is to be stabilized at a desired value differing by a predetermined amount from the frequency of a pilot oscillation generated in said frequency modulation system, frequency adjusting means coupled to said main oscillation generating means, means for mixing said main and said pilot oscillations to obtain a difference oscillation, a circuit including a direct current source and a resistance, means to interrupt the current in said circuit in synchronism with half-waves of like sign of said difference oscillation to produce voltage pulsations across said resistance, means for transforming said voltage pulsations into electrical impulses of like sign having an area substantially proportional to the voltage of said source, an amplitude independent of said oscillation and a duration smaller than the half-periods of the highest frequency of said difference oscillation, means to integrate said impulses to produce a potential substantially proportional to the frequency of said difference oscillation and to said voltage, means to inject a fraction of the voltage

of the direct current source in opposition to the said potential to produce an output voltage compensated to zero independently of voltage variations in said source at frequency values of the main oscillation equal to said desired value, means to connect said integrating means to said frequency adjusting means, and means to vary the amplitude of said output voltage proportional to intelligence to produce frequency modulation of said main oscillation.

9. In a frequency modulation system, a main oscillator the frequency of which may vary about an adjustable stabilized value differing by a predetermined amount from the frequency of a crystal controlled pilot oscillator, means for radiating the energy of said main oscillation, means for adjusting the frequency of the main oscillator, means for mixing said main and said pilot oscillations to produce a difference oscillation, a thermionic tube having a control electrode, an anode and a cathode, a resistance and a direct current source serially connected between the anode and cathode, a potentiometer connected in shunt with said direct current source, means to apply said difference oscillation to said control electrode to produce voltage pulsations across said resistance in synchronism with half waves of like sign of said difference oscillation, means to transform said voltage pulsations into electrical impulses of like sign having an area substantially proportional to the voltage of said source, an amplitude independent of said difference oscillation and a duration smaller than the half periods of the difference oscillation comprising a condenser having one electrode coupled to the anode circuit of said tube, two half wave rectifiers having anode and cathode electrodes, and a load resistance, the cathode of one of said rectifiers and the anode of the other rectifier being coupled to the other electrode of the condenser, one terminal of the load resistance being coupled to the other electrode of one of said rectifiers, and the other electrode of the second of said rectifiers and the other terminal of the load resistance being coupled to the movable arm of said potentiometer, and means to integrate said impulses to produce a potential substantially proportional to the frequency of said difference oscillation and to the voltage of said source comprising a filter coupled to said load resistance, said movable tap being positioned at a point at which the voltage thereat has a value substantially equal and opposite in sign to the value of said potential at a frequency value of said difference oscillation equal to the mean frequency value of said difference oscillation, said filter circuit being connected to said frequency adjusting means to maintain said main oscillation at the desired stabilized value, and means inserted between said filter circuit and said frequency adjusting means for additionally varying the amplitude of said compensated output voltage proportional to intelligence to produce frequency modulation of said main oscillation about said stabilized value.
